UNITED STATES PATENT OFFICE

2,497,560

STOP MOTION FOR BRAIDING MACHINES

Joseph Robideau, Cumberland, R. I.

Application August 26, 1948, Serial No. 46,282

8 Claims. (Cl. 87—19)

1

This invention relates to a braiding machine, more particularly that type in which there is an upstanding guide post on the quoit plate and through which warp yarns extend to be incorporated into the braiding structure, by the yarns from the carrier being braided about these yarns.

In this type of machine although stop motions are provided upon the exhaustion or failure of the yarns which are carried on the bobbins of the carrier, there is no means for stopping the machine upon the failure of the yarn which extends through guide posts. Accordingly, the machine may continue to operate for a considerable length of time after the yarn which extends through the guide posts has failed.

One of the objects of this invention is to provide a means for stopping the machine when the yarn which extends through and is guided by the guide posts fails.

Another object of this invention is to utilize the stop motion already provided actuated by a mechanism on the carrier for the stopping of the machine.

Another object of the invention is to provide a stop motion which is partly carried by the guide post and partly carried by the carrier but which will come into co-active relation upon the breaking of the yarn which is guided through the guide post.

Another object of this invention is to utilize gravity as the force which moves the parts into stop motion actuating position.

With these and other objects in view, the invention consists of certain novel features of construction, as will be more fully described and particularly pointed out in the appended claims.

In the accompanying drawings:

Figure 1 is an elevation with the lower part of the machine in section showing the fragmental portion of a braider machine which incorporates this invention;

Figure 2 is a sectional view on line 2—2 of Figure 1;

Figure 3 is an elevation of a fragmental part of a carrier illustrating the attachment to the carrier which incorporates the invention herein;

Figure 4 is an end view of that portion of the carrier shown in Figure 3; and

Figure 5 is a sectional view on line 5—5 of Figure 3 of the carrier shown in Figure 3.

In proceeding with this invention I provide a lever which is pivoted on the guide post through which the warp yarns are guided in a braider machine, and I hold this lever in raised position by a link beneath which the warp yarn is looped

2

and raised by the tension of the warp yarn as it is taken up by the take-up mechanism for the work. When this warp yarn breaks and permits the lever to be lowered, the lever is then in a position to engage a trigger which holds a member or arm on the carrier in an elevated position so that it will not engage the stop motion mechanism of the machine. However, when the member on the post engages the trigger and moves the same, the arm on the carrier is then permitted to drop to a position to engage the stop motion of the machine and cause the machine to be stopped just the same as if the weight on the carrier had dropped to its lower position by failure of yarn of the bobbin on the carrier.

With reference to the drawings, 10 designates the top plate of a braider carrier machine in which there is provided the serpentine raceway 11 for guiding a braider carrier 12 by means of gear mechanism 13 located between the top plate 10 and bed plate 14, the carrier being moved by means of the horns 15 on the gears to pass the same through the serpentine raceway for intertwining the yarn which is carried by the braider carrier.

The braider carrier 12 consists of a base 15 having flanges 16 and 17 to engage either side of the top plate 10. A bobbin spindle 18 extends upwardly from the standard portion 19 of the base to receive the bobbin 20 which is rotatably mounted upon this spindle. This bobbin has ratchet teeth 21 at its lower end to be engaged by the pawl 22 to control the let-off of the yarn on the bobbin 20. This pawl is actuated by the link 22 slidable on the guide rod 23 and pressed downwardly by a spring 24. This link is actuated by the weight 25 guided on the guide rod 26 and pressed downwardly by the long spring 27. This weight carries the usual hook 28 beneath which the yarn extends so that as the yarn is taken up at the may pole, the weight will lift upwardly to trip the pawl and permit more yarn to be fed in a usual manner. The weight 25 carries at its lower portion a means for actuating the stop motion of the machine in a usual manner, and as the weight is usually lifted and not in its lowermost position, the stop motion will not be actuated until the yarn on the bobbin breaks when the weight will drop to its lower position to cause actuation of the stop motion.

I have attached to the usual braider carrier an arm 30 which is generally L-shaped as shown in Figure 5 having a portion 31 and another portion 32 at right angles thereto, which second portion is pivoted to the standard 19 on the pivot

pin 33 which extends through the latch 22. When this arm 30 is in its lowermost position, as shown in dotted lines in Figures 1 and 3, its portion 31 will serve the same function as the stop motion portion of the weight 25 and will engage the stop motion of the machine to stop the machine.

In order to hold this arm 30 in raised position, which is inoperative so far as engagement with the stop motion is concerned, I have provided a trigger 35 having a mid portion 36 which is pivoted or rockably mounted about a vertical axis as at 37 (see Figure 3 or 4) with a finger portion 38 extending beneath the arm 30 to support the same and a second finger portion 39 extending outwardly away from the standard 19 so that if this portion 39 is engaged and the trigger rocked about its pivot 37, the arm 30 will be released and will drop by gravity. In order to retain the trigger in a position whereby it engages the arm 30, I have provided a spring designated generally 40 which has a mid portion 41 pivoted in the standard 19 as shown best in Figure 4, with one arm portion 42 extending up to engage the finger 39 to swing the trigger so that its finger 38 will extend beneath the arm 30 and support it; while at the other side of this pivoted portion 41 there is a finger 43 which engages the base of the carrier and serves to maintain a tension on this spring for swinging the trigger as above described.

In the center of the quoit plate 45 there is a post designated generally 46 through the center 47 of which a warp yarn 48 (see Figure 1) extends. This warp yarn is drawn from a reel or some supply beneath the base plate of the machine and usually is provided with some tension means to afford some control upon it. In the present case, this post serves as a support for a member or lever 49 (see Figures 1 and 2) which is pivoted as at 50 on the post and will tend to swing by gravity into the position shown in dotted lines in Figure 1, and when in this dotted-line position will engage the trigger finger 39 carried by the carrier of the machine and which has above been described. However, in order to hold this member or lever upwardly, I have provided a link 51 which engages the lever and which is vertically guided as at 52 and provided with a hook 53, beneath which the warp 48 extends so as to lift this link by the tension of the warp yarn 48 and serve to maintain the lever or member in raised position as shown in full lines in Figure 1 and out of the path of movement of the trigger finger 39. However, should there be a failure of tension or a failure by breakage of the warp yarn 48, then the link 51 would permit the lever or member 49 to drop into the dotted line position shown in Figure 1 so that it would then engage the finger 39 of the trigger to swing the trigger to permit the arm 30 to drop into a position to cause it to engage the stop motion of the braider carrier and stop the machine.

I claim:

1. In a braiding machine, a stationary post through which yarn is guided, a movable braider carrier, a stop motion actuating arm pivotally mounted on the carrier to be rocked about a substantially horizontal axis, a trigger mounted for rotational movement about a substantially vertical axis and movable into engagement with said arm to hold the same in inoperative position, said trigger having a projection thereon engageable to rock said trigger out of engagement with said arm to permit the same to be rocked by gravity

to be positioned in the operative position, a guide post on said machine, a member movably mounted on said post in the path of said projection, means engaged by the yarn passing through said post to hold, by tension on the yarn, said member out of the path of said projection but permitting the member to be moved into the projection path upon failure of said tension whereby to engage the projection to cause the arm to move into operative position.

2. In a braiding machine as in claim 1 wherein said member is pivotally mounted.

3. In a braiding machine as in claim 1 wherein a spring assists said trigger in maintaining said arm in inoperative position.

4. In a braiding machine, a movable braider carrier, a stop motion actuating arm mounted for movement about a substantially horizontal axis, a trigger mounted on said carrier for movement about a substantially vertical axis and movable into engagement with said arm to hold the same in the inoperative position, said trigger having a projection engageable to move said trigger to disengage the same from said arm to permit the arm to be moved by gravity to an operative position and means for engaging said projection to disengage said trigger from said arm.

5. In a braiding machine, a stationary post through which yarn is guided, a movable braider carrier, a stop motion actuating arm pivotally mounted on said carrier for rocking movement about a substantially horizontal axis, a trigger rockably mounted on said carrier and having an offset portion movable to be positioned into engagement with said arm to hold the same in an inoperative position, said trigger having a projection engageable to rock said trigger to disengage said offset portion from engagement with said arm to permit the arm to be moved by gravity to an operative position, and means carried by said post movable into the path of said projection for engaging and rocking the same.

6. In a braiding machine, a stationary post through which yarn is guided, a movable braider carrier, a stop motion actuating arm pivotally mounted on said carrier for rocking movement about a substantially horizontal axis, a trigger rockably mounted on said carrier to be moved about a substantially vertical axis and having an offset portion movable to be positioned into engagement with said arm to hold the same in an inoperative position, said trigger having a projection engageable to rock said trigger to disengage said offset portion from engagement with said arm to permit the arm to be moved by gravity to an operative position, and means carried by said post movable into the path of said projection for engaging and rocking the same.

7. In a braiding machine, a movable braider carrier, a stop motion actuating arm mounted for movement about a substantially horizontal axis, a trigger mounted on said carrier for rocking movement about a substantially vertical axis and having an offset thereon movable to be positioned into engagement with said arm at a location beneath said arm to hold the same in an inoperative position, said trigger having a projection engageable to rock said trigger to move said offset from beneath said arm to permit the arm to fall by gravity in an operative position, and means for engaging said projection to rock said arm.

8. In a braiding machine, a movable braider carrier, a stop motion actuating arm mounted

for movement about a substantially horizontal axis, a trigger mounted on said carrier for rocking movement about a substantially vertical axis and having an offset thereon movable to be positioned into engagement with said arm at a location beneath said arm to hold the same in an inoperative position, said trigger having a projection engageable to rock said trigger to move said offset from beneath said arm to permit the arm to fall by gravity in an operative position, and means for engaging said projection to rock said arm, and a spring engaging said projection

to assist said trigger in maintaining said arm in inoperative position.

JOSEPH ROBIDEAU.
